UNITED STATES PATENT OFFICE.

WILLIAM S. REED, OF LEOMINSTER, MASSACHUSETTS, AND THOMAS JOSEPH WALSH, OF LONDON, ENGLAND, ASSIGNORS TO THE W. S. REED TOY COMPANY, OF LEOMINSTER, MASSACHUSETTS.

MECHANICAL TOY OR GAME.

SPECIFICATION forming part of Letters Patent No. 320,501, dated June 23, 1885.

Application filed February 12, 1885. (No model.)

To all whom it may concern:

Be it known that we, WILLIAM S. REED, of Leominster, in the county of Worcester and State of Massachusetts, United States of 5 America, and THOMAS JOSEPH WALSH, of London, England, have invented a Mechanical Toy or Game, of which the following is a full, clear, and exact description, reference being had to the accompanying drawings, making 10 part of this specification, in which—

Figure 1 is a perspective view of one form of mechanical toy embodying our invention. Fig. 2 is a vertical section through the center of the same; Fig. 3, a transverse section on the 15 line $x-x$ of Figs. 1 and 2; Fig. 4, an elevation of the front of another style of mechanical toy embodying our invention; Fig. 5, a rear elevation of the same; Fig. 6, a transverse section on the line $y-y$ of Figs. 4 and 5; Fig. 7, detail, to be referred to.

Our present invention has special reference to that class of mechanical toys or games provided with a target, and in which a ball or other missile or object is projected against it; 25 and this invention consists in a series of blocks, tablets, or figures (either colored, illustrated, or not) arranged within a case holder or receptacle of any desired form, and provided with one or more openings through which the blocks, &c., are exposed to view and struck and displaced by a projectile propelled by hand or otherwise, the blocks, &c., being successively brought into line with an opening in the case, &c., by a spring, by gravity, or by 30 weight of superincumbent blocks, the aforesaid invention being readily applied to a miniature house, castle, tower, gun-boat, steam-boat, bridge, car, or other vehicle, object, or thing.

40 In the said drawings, A represents an upright frame, the front of which is finished to resemble a miniature tower. a represents an arched gateway or opening at its bottom. $b c d e f g$ a series of circular openings or windows 45 thereover.

On the inside of the tower are secured two parallel cleats, h , extending vertically from top to bottom thereof, the space between the cleats being for the reception of a series of 50 blocks or tablets, B, having illustrations de-

lineated thereon, if desired. The inner edges of the cleats at the points $i i$, Fig. 7, near the bottom of the tower, slightly overlap the side edges of the blocks or tablets and form guides or ways in which they are capable of sliding, 55 a rectangular opening, k , being formed in the top of the tower, through which the blocks may be entered, the portion of each cleat below the points $i i$ being cut away, so as not to overlap the edges of the lowest block, the width of 60 which corresponds to the width of the way at this point.

Through the arched gateway a , and the several openings, $b c d e f g$, above it, are seen the blocks or tablets, with any design which may 65 be delineated thereon.

C represents a horizontal floor or platform extending out from the base of the tower and capable of being readily detached therefrom for convenience in folding or stowing for transportation. 70

At the outer end of the platform is located a spring-plunger, D, of the following construction:

k' is a block secured to the end of said platform and having a circular longitudinal hole, l , bored centrally through it, for the reception of one end of the plunger D, which slides therein, the portion of the plunger outside of the block being surrounded by a stiff spiral spring, 75 m , one end of the spring being secured to the inner end of the block and the other end bearing against an enlargement or head, n , of the plunger. The opposite end of the plunger has an annular groove or channel formed 80 therein, into which fits a spring-catch, r , located at the front of the block k' , when the plunger is drawn back against the resistance of the spring, as seen in Fig. 2. The release of the power thus accumulated causes the 85 plunger to be thrown forcibly against the ball p , which is projected against the lower target-block, the result being the displacement of the target from its position behind the gateway-opening a and the descent of 90 the next block above to occupy its place, the weight of the blocks insuring their successive appearance in line with the opening a to be struck and displaced by the ball in the 95 manner previously described. 100

A series of targets, of any desired shape, design, or color, may be pressed upward by a follower actuated by a spring until they are in turn brought into line with an upper opening, 5 *g*, in the tower and be displaced by a ball or other missile thrown by a spring-plunger or other device or by hand, in which a suitable stop would be required to limit the upward movement of the targets as they arrive at the 10 firing position. Where a vertical way having a number of openings and targets of various colors are employed—one red, one white, one blue, another green, &c.—a pleasing effect will be realized by the exhibition of these various 15 colors at one time and by a single glance, and the disappearance of one colored target after another from its firing position is also unique and interesting.

In Figs. 4, 5, and 6 our invention is shown 20 in its application to a house, *E*, having a horizontal guideway, *s*, for the blocks to slide in, a follower, *v*, having an elastic cord or band secured thereto, being employed for automatically advancing the blocks in line with the 25 doorway or opening *u* under the roof as fast as the one in position has been displaced by the ball or other object or thing, a suitable stop, *w*, being employed to limit the advance movement of the spring.

30 A receptacle for holding blocks, tablets, images, figures, or other objects or things to slide therein and be displaced therefrom in the manner set forth may be so constructed as to represent a boat, bridge, car, vehicle, or 35 edifice of any design, and, instead of being exposed through an opening therein, the targets in their firing position may be brought to view at the side, top, or bottom of the receptacle, in which case the other openings referred to 40 may be retained or dispensed with, the whole

constituting a novel and instructive toy for the young.

I claim—

1. As an improvement in mechanical toys or games, a holder case or receptacle of any 45 desired design having a suitable guideway and one or more openings, in combination with a series of target-blocks, tablets, figures, or images successively exposed to view by spring-actuating mechanism or by gravity after each preceding one is displaced by a ball or other missile or object, substantially as shown and described.

2. A holder case or receptacle having a vertical guideway and one or more openings, a 55 series of target-blocks, tablets, &c., either colored, illustrated, or not, and a spring for discharging or projecting a ball or other object thereat, whereby one target is displaced and the next one brought into line in its exposed 60 or firing position, substantially as set forth.

3. In combination, a holder having a guideway, a series of targets, *B*, a follower actuated by a spring, and a stop for limiting the advance movement of and arresting the targets 65 when in their firing position, as described.

Witness my hand this 20th day of January, 1885.

WILLIAM S. REED.

In presence of—

N. W. STEARNS,
H. W. STEARNS.

Witness my hand this 18th day of December, 1884.

THOMAS JOSEPH WALSH.
